UNITED STATES PATENT OFFICE.

JULIUS F. ADAMS, OF PITTSBURGH, PENNSYLVANIA; ANNA ADAMS LAUER ADMINISTRATRIX OF SAID JULIUS F. ADAMS, DECEASED.

DESIGN FOR A GAS HEATER.

Application filed November 28, 1924, Serial No. 11,520. Term of patent 7 years.

To all whom it may concern:

Be it known that I, JULIUS F. ADAMS, a citizen of the United States, residing at Pittsburgh, in the county of Allegheny and State of Pennsylvania, have invented a new, original, and ornamental Design for Gas Heaters, of which the following is a specification, reference being had to the accompanying drawing, forming part thereof.

Fig. 1 represents a front view of my ornamental design for gas heaters, and Fig. 2 is a side view of the same.

I claim:

The ornamental design for a gas heater, as shown.

JULIUS F. ADAMS.
